Patented June 28, 1921.

Inventor -

J. R. Rodgers
or Cook & McCauley

MS.

UNITED STATES PATENT OFFICE.

JESSE R. RODGERS, OF UNION CITY, TENNESSEE, ASSIGNOR OF ONE-HALF TO WAY-
MAN C. JOPLIN, OF ST. LOUIS, MISSOURI.

SHOE-DISPLAYING DEVICE.

1,383,154.

Specification of Letters Patent. Patented June 28, 1921.

Application filed October 25, 1920. Serial No. 419,291.

To all whom it may concern:

Be it known that I, JESSE R. RODGERS, a citizen of the United States of America, and a resident of Union City, in the county of 5 Obion and State of Tennessee, have invented certain new and useful Improvements in Shoe-Displaying Devices, of which the following is a full, clear, and exact description, reference being had to the accompanying 10 drawings, forming a part of this specification.

This invention relates to improvements in shoe displaying devices, the main object being to provide a simple and inexpensive 15 means for clearly and accurately showing the shape, color, quality and workmanship of a large number of shoes. Another object is to enable a traveling shoe salesman to very easily and quickly display the shoes 20 in such a manner that the customer can very readily select the desired shoes without unnecessary confusion which ordinarily results from inspection of many different sample shoes. A further object is to avoid the 25 labor and expense heretofore incurred by the manufacture and transportation of a very large number of sample shoes.

Prior to this invention, shoe manufacturers have ordinarily provided each of 30 their traveling salesmen with a sample of each shoe to be displayed, together with several trunks in which the shoes are transported. The many samples show the different lasts or shapes of the shoes, and the 35 different qualities of shoes made in accordance with each last. It is customary to provide each salesman with about three trunks filled with sample shoes, and it is frequently very difficult to transport all of these samples 40 to towns distant from the railroad. In addition to this, there is the expense of excess baggage, drayage to and from hotels, and usually rent for display rooms in the hotels. Considerable time and work is necessary 45 for the removal of many shoes from the trunks and arranging them in the display room, and even though most effectively displayed, the customer is confused in making 50 selections from a large number of sample shoes.

In addition to the trouble and expense of transporting and arranging a confusing display of sample shoes, all large shoe

manufacturers are subjected to the expense of making thousands of sample shoes while 55 their factories could be used to manufacture shoes for the market.

My object is to eliminate almost all of this expense and trouble, and at the same time provide a means whereby the shoes 60 may be more effectively displayed, so as to enable the customer to very easily and quickly select shoes of any desired shape and any desired quality, all of which are displayed to fully show the various shapes 65 of the shoes as well as the quality and colors of the different leathers and the workmanship of the various shoes. This is accomplished through the medium of a certain specific combination of elements including 70 a few selected sample shoes, several series of photographs or the like, each series corresponding to one of the sample shoes, and samples of leather associated with the photographs and sample shoes, as will be hereafter described, to completely illustrate the 75 shape, color, quality and workmanship of each shoe of the series.

With the foregoing and other objects in view, the invention comprises the novel construction, combination and arrangement of parts hereinafter more specifically described and illustrated in the accompanying drawings wherein is shown the preferred embodiment of the invention. However, it is to 80 be understood that the invention comprehends changes, variations and modifications which come within the scope of the claims hereunto appended.

Figure I is an illustration of a sample 90 shoe and a series of photographs associated therewith, each photograph being accompanied by a sample of leather.

Fig. II is a view similar to Fig. I illustrating another class of shoes. 95

Fig. III is an enlarged detail view showing the descriptive matter on one of the photographs.

To illustrate one form of the invention I have shown a sample shoe 10 representing a 100 series or class of shoes. This sample may represent either the quality or shape of other shoes in the same class. For example, in Fig. I I have shown a sample shoe 10 as the representative of a class of shoes to be 105 known as "Series A", which term may be

used to indicate shoes of the highest quality, all selling for about the same price. The quality and general workmanship of the shoes in "Series A" is clearly shown by the sample.

A series of pictures 11, preferably photographs, is associated with the sample shoe 10 to represent various shoes of the same class as the sample, and a sample of leather 12 is secured to each photograph. The several photographs of this series may be mounted on a backing sheet 13 whereby they are united and retained in a predetermined consecutive order. The photographs bear an essential relation to each other as well as to the sample shoe, for all of these elements represent shoes of the same class. Several samples and several series of photographs will be used to display a complete line of shoes, and it is therefore important to identify each sample with a particular series of photographs. As an identification means, the sample shoe 10 may be provided with a tag 14 bearing the title "Series A" and the same title may appear on the backing sheet 13 to which all of the photographs 11 and samples of leather 12 are secured.

In Fig. I, the photographs represent shoes of different shapes, all conforming in quality, workmanship and price to the sample shoe 10, and each shoe is known by a name indicating its shape or last. On the first photograph in the series, the word "Olive" appears for the purpose of indicating the "Olive" last, and the same photograph is provided with the characters A-1 indicating the first shoe in series A. The letter A indicates the quality of the shoe. On the remaining photographs 11, the names of the lasts are shown by the words Labadie, Maffitt, Bartmer, etc., and the quality and numbers of these shoes are indicated by A-2, A-3, A-4, etc. In the preferred form of the invention each photograph is also provided with a brief description of the shoe, as illustrated by Fig. III, together with a statement showing different dimensions of the shoes conforming to the photograph.

On the tag 14 accompanying the sample shoe 10, the words "Olive last shoe A-1" set forth the shape, quality and number of the sample shoe. The photographs 11 and samples of leather 12 clearly show the shape, color and general appearance of each shoe, and I prefer to illustrate the accuracy of these representations by making one of the photographs and one of the leather samples represent the sample shoe 10. In Fig. I the first picture in the series is a photograph of the sample shoe 10, and it is accompanied by a sample of the leather in the sample shoe 10. This feature is of some importance, for it shows the accuracy of the unique display device and enables the customer to more readily select the shoes after

the accuracy of the device has been determined by a comparison of the sample shoe with its photograph and leather sample.

In Fig. II I have shown a series of photographs 11' mounted on a backing sheet 13' and the sample shoe 10' associated therewith, each photograph being provided with a sample of leather 12'. This combination of elements is provided with letters, numbers, and descriptive words which are clearly shown by the drawing and which will be readily understood in view of the description of the similar combination shown by Fig. I. The combination shown by Fig. II represents shoes of the second quality, as indicated by the letter B. The shoe B-1 is represented by the sample shoe as well as by the sample of leather and photograph B-1.

The sample shoes 10 and 10' are, of course, perfect illustrations of the shape of shoes made on certain lasts, the sample 10 conforming to the "Olive" last and the sample 10' conforming to the "Labadie" last. The photograph A-2 in Fig. I illustrates a class A shoe made on the "Labadie" last, and a class B shoe conforming to this last is shown by the sample 10', so the photograph A-2 can be compared with the sample shoe 10' as well as with the sample shoe 10 to obtain a thorough understanding of the appearance and quality of the shoe A-2. In the same manner, "Olive" shoe represented by photograph B-2 (Fig. II) is shown partly by the photograph and partly by the sample of leather, while its shape and general appearance is shown by the sample shoe 10 made on the "Olive" last.

It will be understood that additional sample shoes can be associated with photographs and samples of leather in the manner herein shown, to accurately represent a complete line of shoes, and in many instances the sample associated with a series of photographs can be advantageously used in connection with a photograph in another series.

In the selection of shoes, the customer is especially interested in the quality or price and the shape or style. If the highest quality is desired, all of the shoes in this class can be easily and quickly selected by references to the photographs and samples of leather in series A and by an examination of the sample shoe 10. Some of the other sample shoes will aid in showing the general appearance of the photographed shoes in series A. Shoes of any quality and any style can be very easily selected.

The new combination and arrangement of elements herein shown, including a few sample shoes and the groups of photographs and samples of leather associated therewith, produces a simple and inexpensive display device from which the desired shoes can be easily selected without confusion, and this compact device can be easily transported.

without the expense and trouble ordinarily incurred by the transport of several trunks of shoes. Furthermore, by combining the several elements with each other as 5 herein pointed out, I produce a complete and accurate representation of the shape, color, quality and workmanship of a very large number of shoes which have heretofore been represented by an expensive sample of 10 each shoe to be displayed.

I claim:

1. In a shoe displaying device, the combination of a sample shoe, a series of pictures representing shoes of the same class as the 15 sample shoe, and samples of leather combined with said pictures to show the quality and color of leather in the shoes represented by the pictures, said sample shoe, pictures and samples of leather being associated with 20 each other to show the shape, color, quality and workmanship of a series of shoes of the same class.

2. In a device for displaying shoes differing in shape, color, quality and workmanship, the combination of different sample shoes, a plurality of series of pictures of 25 shoes to be displayed, each series of pictures representing shoes of the same class as one of said sample shoes, and samples of leather 30 combined with the respective pictures to show the quality and color of leather in the shoes represented by said pictures, said sample shoes, pictures and samples of leather being associated with each other to show the 35 shape, color, quality and workmanship of the different classes of shoes represented by said pictures.

3. In a device for displaying shoes differing in shape, color, quality and workmanship, the combination of different sample 40 shoes, a plurality of series of photographs of the shoes to be displayed, each series of photographs including a photograph of one of the sample shoes and photographs of a 45 series of shoes of the same class as said sample shoe, and samples of leather secured to the respective photographs to show the quality and color of leather in the shoes represented by said photographs, said sample 50 shoes, photographs and samples of leather being associated with each other to show the shape, color, quality and workmanship of

the different shoes represented by said photographs.

4. In a device for displaying shoes differing in shape, color, quality and workmanship, the combination of different sample shoes, a plurality of series of photographs of the shoes to be displayed, each sample shoe being provided with identification 55 means indicating the series of photographs with which it is associated, each series of photographs including a photograph of one of the sample shoes and photographs of a series of shoes of the same class as said sample shoe, each of said series of photographs also including a photograph of a shoe corresponding to a sample shoe in a class represented by another of the series of photographs, and samples of leather secured to 60 the respective photographs to show the quality and color of leather in the shoes represented by said photographs, said sample shoes, photographs and samples of leather 65 being associated with each other to show the shape, color, quality and workmanship of the different shoes represented by said photographs.

5. In a device for displaying shoes differing in shape, color, quality and workmanship, the combination of a series of different sample shoes each showing the quality and workmanship of a series of shoes to be displayed, a plurality of series of photographs of the shoes to be displayed, each 80 sample shoe being provided with identification means indicating the series of photographs with which it is associated, each series of photographs comprising a picture of one of said sample shoes and pictures of 85 other shoes conforming in quality and workmanship to the same sample shoe, each series of photographs also including a picture of a shoe conforming to the shape of another of said sample shoes, each photograph being 90 provided with a description showing different dimensions of shoes conforming to the photograph, and samples of leather secured to the respective photographs to show the quality and color of leather represented 95 by the photographs.

In testimony that I claim the foregoing I hereunto affix my signature.

JESSE R. RODGERS.
